UNITED STATES PATENT OFFICE.

EUGENE TOMPKINS, OF ADDISON, NEW YORK.

NAILING-MACHINE.

1,135,335.

Specification of Letters Patent. Patented Apr. 13, 1915.

Application filed August 20, 1914. Serial No. 857,716.

To all whom it may concern:

Be it known that I, EUGENE TOMPKINS, a citizen of the United States, residing at Addison, in the county of Steuben and State of New York, have invented certain new and useful Improvements in Nailing-Machines; and I do declare the following to be a full, clear, and exact description of the invention, such as will enable others skilled in the art to which it appertains to make and use the same.

This invention relates to new and useful improvements in nailing machines and more particularly to a machine for automatically feeding nails to a guiding plunger and the primary object of the device is to provide a machine of this character which is of improved construction, comparatively inexpensive to manufacture and which is extremely efficient in use.

A further object of the invention resides in providing an improved construction for receiving the nails from the magazine or chute and feeding the same to the driving plunger.

Still another object of the invention resides in providing a device which is so assembled that the same may be readily taken apart for cleaning purposes or for the purpose of replacing an injured part when desired.

With these and other objects in view, my invention consists in the novel features of construction, combination and arrangement of parts as will be hereinafter referred to and more particularly pointed out in the specification and claims.

In the accompanying drawings forming a part of this application:—Figure 1 is a side elevation of a device constructed in accordance with my invention: Fig. 2 is an end elevation thereof; Fig. 3 is a top plan view of the same; Fig. 4 is a fragmentary side elevation of the device, opposed to that shown in Fig. 1. Fig. 5 is a vertical section through the operating portions of the device, showing the plunger in its normal position; Fig. 6 is a similar view showing the plunger in its lowered and operative position; Fig. 7 is a fragmentary side elevation showing the parts in their normal positions as disclosed in Fig. 5; Fig. 8 is a similar view showing the parts in the operated position as disclosed in Fig. 6; Fig. 9 is a horizontal section as seen on line 9—9 of Fig.

7; Fig. 10 is a similar view as seen on line 10—10 of Fig. 8; Fig. 11 is a vertical transverse section as seen on line 11—11 of Fig. 8; Fig. 12 is a similar view taken through the lower end of the barrel and the jaws 60 therein; Fig. 13 is an inverted perspective view of one of the side plates of the device; Fig. 14 is a similar view with one of the sliding plates applied in position thereon and; Fig. 15 is a perspective view of the 65 aforesaid sliding plate removed.

In describing the invention I shall refer to the drawings in which similar reference characters designate corresponding parts throughout the several views and in which— 70

1 designates a casting which is substantially L shaped, one arm of which is designed tubular in effect as shown at 2 to form a barrel or the like. The other arm thereof which is designated in the drawings 75 as 3 forms substantially a housing as will be hereinafter more particularly set forth.

Mounted to move vertically in the barrel 2 is a plunger 4, the lower end of which is tapered and designed to engage the head 80 of a nail readily while the upper end thereof has a knob or handle 5 mounted thereon. The lower portion of the barrel 2 which has the outline thereof square in cross section has a pair of opposite side faces there- 85 of cut away to receive therein a pair of spring held jaw members 6. The inner opposed faces of these jaws 6 are grooved to provide a central channelway 7 therein for receiving a nail in a manner to be herein- 90 after more particularly set forth. This channelway 7, however, tapers outwardly toward its upper end and is designed to readily receive the lower tapered end of the plunger 4 therein to spread said jaw 95 members readily upon the lowering of said plunger to its effective position.

Formed on a portion of the barrel 2 just above the arm portion 3 of the casting 1 is a boss 8 which has an eye formed therein 100 receiving one angularly bent end of a strong wire spring member 9. This wire spring member continues outwardly from the bent end thereof in a direction toward the outer end of the arm 3 of the casting and is looped 105 a number of times as shown at 10 whereupon the same is directed or drawn toward the barrel and looped therearound as shown at 11. The free end of the spring is then clamped to an arm portion thereof by means 110

of a clamp 12. The loops 10 of the spring member are positioned on opposite sides of an upstanding arm or projection 13 formed on the outer end of the arm portion 3 of the casting 1 and in view of the particular position of this spring member 9 with respect to the casting, the upper arm portion of said spring bearing the loop 11 has a strong tendency to move upwardly.

10 Extending transversely through the plunger 4 at a point intermediate of its ends is a bolt or pin 14 which projects through slots 15 formed at diametrically opposite points on the barrel 2. These projecting portions 15 of the pin or bolt 14 are adapted to rest upon the loop 11 of the spring 9 and said spring, therefore, retains the plunger 4 normally in a raised and inoperative position. Said plunger is only forced downwardly 20 against the tension of said spring member.

As stated above, the arm portion 3 of the casting 1 forms substantially a housing and this housing is for the purpose of receiving and feeding the nails to the jaws 6 at which 25 point the same are driven downwardly by the driving plunger. This housing or the like 3 is designed somewhat channel shaped in cross section, having one side wall and top and bottom walls. The one end 30 thereof communicates with the interior of the barrel through a channel or the like 16. The upper and lower walls of this housing or the like 3 are grooved as shown at 17 to receive therein the upper and lower edges of 35 a sliding plate 18. The upper edge of the plate 18 is offset for a portion of its length as shown at 19 for a purpose to be herein-after and more particularly set forth and the side wall of the housing or the like 3 is adjacent its upper edge is also grooved 40 longitudinally as shown at 20 to register with this offset upper edge 19 of the plate 18. Applied to the open side of the housing or the like 3 is a covering plate 21, the same 45 forming an opposite side wall for the housing 3 and a retaining means for the siding plate 18. The upper edge of this covering plate 21 is also offset as shown at 22 similar to the offset upper edge of the plate 18. 50 This plate is removably applied in position and has near one end a longitudinal slot 23 formed therein through which projects a stud or the like 24 carried on the plate 18. The purpose of this laterally extending stud 55 24 will be hereinafter and more particularly set forth.

Projecting laterally from the upper end of the upstanding arm or projection 13 on the portion 3 is a stud 25 upon which is fulcrumed a bell crank lever 26, such fulcrum point being at the junction of the arms of the lever. Connected with the end of one arm of the lever is a link 27 which also has pivotal connection with the aforesaid stud 60 24 which projects through the slot 23. The

end of the opposite arm 26 of said lever has a link 28 connected therewith, said latter link also having pivotal connection with a laterally extending stud 29 carried at one end of the aforesaid clamp 12. From this 70 construction it will be seen that upon the pressure downwardly of the plunger 4, the one arm of the spring member 9 will be forced downwardly causing the bell crank lever 26 to be rocked on its fulcrum point 75 thus moving the sliding plate 18 to the right in Fig. 5. Upon release of the pressure on the lever and the plunger 4 the latter will be returned to its initial position as will also the sliding plate 18.

As stated above, the sliding plate is designed for the purpose of feeding nails through the channel 16 to the gripping jaws 6 to be driven therefrom into an object by means of the driving plunger. In order to 80 feed the nails to this device I provide a magazine or the like 30 which is constructed of a pair of spaced plates or the like, adjustably secured in spaced relation to one another by means of the clamping members 85 31 at the ends thereof. Connected with the outer end of this magazine 30 is a hopper (not shown) which permits the nails to be fed readily to said magazine and the clamping member 31 at the inner end of the latter 90 is removably secured to a bracket 32 which is angular in design and has one arm thereof secured to the permanent side wall of the housing 3. The inner end of the magazine 95 is designed to abut the outer side face of the plate 21 and at this point said plate is provided with a vertical slot 33 which terminates at the upper edge of said plate and continues downwardly to a point adjacent the lower edge thereof. This slot 33 admits 100 nails fed from the magazine to be readily received through the plate 21 to abut against the outer side face of the plate 18 which, in its normal position, has its inner edge inwardly of this vertical slot 33. As the nails 105 are fed to this slot 33 from the magazine, the head portions thereof are adapted to rest on the offset or cut away portions 19 and 22 of the plates 18 and 21 respectively, while the shank portions of said nails are 110 received directly in the slot 33 to fit against the outer face of the plate 18, as clearly 115 shown in Fig. 7 of the drawings.

The plate 21 is also provided with a horizontal slot 34 which intersects the slot 33 120 and the inner face of said plate 21 is reduced in thickness from its lower edge upwardly for a considerable portion of its height to provide a channel way or groove 35. This channelway or reduced portion 125 on the inner face of the plate 21 slidably receives therein an additional sliding plate or the like 36, the latter having at its one end an angular projection 37 thereon which projection has its free end tapered and bent out- 130

wardly, to form a spring tongue 38. When this plate 36 is properly applied to the inner face of the plate 21 the spring tongue 38 thereof aligns with the horizontal slot 34 in the plate 21 and is designed to pass across the latter as said plate 36 is moved longitudinally of the plate 21. A portion of the upper edge of the plate or strip 36 when the latter is applied on the inner face of the plate 21, registers with the lower wall of the slot 23 in said plate 21 and formed on said upper edge intermediate the end of said plate is a projection 39 while an additional projection 40 is provided at the end of said strip or plate 36 opposite that having the angular projection 37 thereon. The inner face of the plate 21 is provided with a projection 41 formed in the channelway 35 directly in the path of the member 36. This projection 41 is, as clearly shown in Figs. 13 and 14 of the drawings, intersected by the vertical slot 33 in the plate 21 and one edge of said projection is adapted to receive thereagainst one edge of the angular projection 37 while the opposite side edge thereof receives thereagainst one side edge of the projection 39 so as to limit the sliding movement of said member 36 in both directions. That portion of the member 36 between the projections 39 and 40 receives the stud 24 thereover, it being understood that this stud projects through the slot 23 in the plate 21. At a certain position in the movement of the plate 18 this stud 24 will contact with the side edge of the projection 40 and cause the member 36 to be moved outwardly with the plate 18. The normal position of this member 36 is such as to dispose the free end of the spring tongue 38 inwardly of the vertical slot 33 so that when said member 36 is moved outwardly with the plate 18, said spring tongue will be moved across the vertical slot 33 in the plate 21. By so doing, the one nail which is always positioned in this slot against the plate 18 will be gripped thereby. The tendency will be to force this nail inwardly inasmuch as this tongue 38 is formed of spring metal and in such position further feeding of the nails into the slots will be prevented. Upon a continued movement outwardly of the plate 18 through the complete downward pressure of the plunger 4, the inner edge of the plate will pass outwardly beyond the vertical plane of the slot 33 and the nail which has just been referred to as being gripped by the spring tongue 38, will be forced inwardly against the inner face of the permanent wall of the housing 3, such position being clearly shown in Figs. 10 and 11 of the drawings. Upon release of pressure from the plunger 4, the plate 18 will be returned to its initial position under tension of the spring 9 and in returning, the inner edge of said plate will contact with the nail and force the same through the

channel 16 to the gripping jaws 6 which will hold the nail until the plunger is again forced downwardly to drive the same therefrom. It will be understood that when the nail is in a position against the inner face of the wall of the housing 3, as shown in Figs. 10 and 11 of the drawings, the head thereof rests partially upon the upper offset edge 19 of the plate 18 and partially within the groove 20. Upon the return of the plate 18 to its initial position the stud 24 projecting through the slot 23 of the plate 21 will contact with one side edge of the projection 39 of said member 36 thus causing the latter member also to be returned to its initial position and upon such return the spring tongue 38 will be clear of the vertical slot 33 to permit an additional nail from the magazine to be fed to said slot as shown in Fig. 9 of the drawings. The device is then in position to have the operation repeated as above described and it will be seen that each time one nail is driven from the device, another nail is simultaneously fed thereto. In order to permit this device to be properly applied to the edge of a box or crate, as seen in Figs. 4, 5 and 6 of the drawings, a gage or the like 42 is provided. This gage 42 is of Y-shaped design and removably applied to one face of the lower portion of the barrel 2. 95

One of the essential objects of the invention is the provision of a device which may be readily assembled or disassembled when desired and in carrying out this object, the various parts are removably applied in position. Such may be readily seen from the drawings wherein bolts, studs, brackets and the like are all removably applied. In order to aid in carrying out this idea, the permanent side wall of the housing 3 has a pair 100 of finger openings 43 formed therein. These openings admit of the stud 24 being readily removed from the plate 18 when it is desired to disassemble the parts. 105

From the foregoing description of the 110 construction of my improved device, the operation thereof will be readily understood and it will be seen that I have provided a device which is simple and durable in construction, inexpensive to manufacture and 115 one which will be very efficient and useful in operation.

While I have particularly described the elements best adapted to perform the functions set forth, it is obvious that various 120 changes in form, proportion and in the minor details of construction may be resorted to, within the scope of the appended claims, without departing from the spirit or sacrificing any of the principles of the invention. 125

Having thus described my invention, what I claim is:

1. A nailing machine comprising an upright barrel, a spring raised plunger there- 130

4
in, a housing extending laterally from and communicating with the lower end of said barrel, said housing having a slot in one side, means for delivering nails to said slot, a 5 feeding plate and a delivering plate mounted side by side in the housing and movable toward and away from the barrel, a spring tongue carried by the feeding plate and adapted to feed nails one at a time through 10 the slot into the housing in advance of the delivering plate, and means operated by reciprocation of the plunger for reciprocating the two plates in the same direction.

2. A nailing machine comprising an up- 15 right barrel, a spring raised plunger therein, a housing extending laterally from and communicating with the lower end of said barrel, said housing having a slot in one side, means for delivering nails to said slot, 20 a feeding plate and a delivering plate mounted side by side in the housing and movable toward and away from the barrel, a tongue carried by the feeding plate and facing away from the barrel, said tongue 25 being adapted to feed nails one at a time through the slot into the housing, when the delivering plate is retracted, means operable by actuation of the plunger for projecting and retracting the delivering plate, and 30 additional means for simultaneously projecting and retracting the feeding plate, but for retracting the latter to less extent than the delivering plate.

3. A nailing machine comprising an up- 35 right barrel, a spring raised plunger therein, a housing extending laterally from and communicating with the lower end of said barrel, said housing having a slot in one side, means for delivering nails to said slot, a 40 feeding plate and a delivering plate mounted side by side in the housing and movable toward and away from the barrel, a tongue carried by the feeding plate and facing away from the barrel, said tongue 45 being adapted to feed nails one at a time through the slot into the housing when the delivering plate is retracted, means operable by actuation of the plunger for projecting and retracting one of the plates, and coacting 50 stops on said plates, whereby actuation of one will simultaneously actuate the other in the same direction.

4. A nailing machine comprising an up- 55 right barrel, a spring raised plunger therein, a housing extending laterally from and communicating with the lower end of said barrel, said housing having a slot in one side, means for delivering nails to said slot, a feeding plate and a delivering plate 60 mounted side by side in the housing and

movable toward and away from the barrel, a tongue carried by the feeding plate and facing away from the barrel, said tongue being adapted to feed nails one at a time through the slot into the housing when the 65 delivering plate is retracted, means operable by actuation of the plunger for projecting and retracting one of said plates, and a pick up mechanism for actuating the other plate from the plate operated by the plunger. 70

5. A nailing machine comprising an up- 75 right barrel, a spring raised plunger therein, a housing extending laterally from and communicating with the lower end of said barrel, said housing having a slot in one side, means for delivering nails to said slot, a feeding plate and a delivering plate mounted side by side in the housing and movable toward and away from the barrel, a tongue carried by the feeding plate and 80 facing away from the barrel, said tongue being adapted to feed nails one at a time through the slot into the housing when the delivering plate is retracted, means operable by actuation of the plunger for projecting 85 and retracting one of said plates, a pair of spaced stops on one plate, and a single stop on the other plate and spaced between the pair of stops, whereby movement of one plate will pick up and move the other plate. 90

6. The combination with nailing driving mechanism, of a housing extending laterally from and adapted to supply nails thereto, said housing having a slot in one side, means for feeding nails to said slot, a 95 feeding plate and a delivering plate mounted side by side in said housing to slide toward and away from the driving mechanism, means on the feeding plate for feeding nails one at a time through said slot into the 100 housing when the delivering plate is retracted, said feeding plate having a longitudinal slot, a stud projecting laterally from the delivering plate into the slot of said feeding plate, and means operable simultaneously with the driving mechanism for moving said delivering plate toward and away from said mechanism, whereupon the stud will slide freely in the slot of the feeding plate throughout a portion of its travel, 110 but will actuate said feeding plate for the remaining portion of its travel.

In testimony whereof I have hereunto set my hand in presence of two subscribing witnesses.

EUGENE TOMPKINS.
